[57] CLAIM

The ornamental design for a toothbrush handle, as shown and described.

DESCRIPTION

FIG. 1 is a top, front and right side perspective view of a toothbrush handle showing my new design;

FIG. 2 is a top plan view thereof;

FIG. 3 is a front elevational view thereof;

FIG. 4 is a right side elevational view thereof where the left side view is a mirror image (unclaimed environmental structure being shown in broken lines);

FIG. 5 is a rear elevational view thereof; and,

FIG. 6 is a bottom plan view thereof.

The broken lines showing the toothbrush bristle structure is for illustrative purposes only and forms no part of the claimed design.
